RAILWAY TRAFFIC CONTROLLING APPARATUS

Charles W. Failor, Forest Hills, Pa., assignor to
The Union Switch & Signal Company, Swiss-
vale, Pa., a corporation of Pennsylvania

Application August 26, 1933, Serial No. 686,970

20 Claims. (Cl. 246—34)

My invention relates to railway traffic controlling apparatus, and more specifically to apparatus for providing broken-down insulated rail joint protection in traffic governing systems which utilize coded rail current for controlling wayside and/or cab signals.

I will describe three forms of railway traffic controlling apparatus embodying my invention, and will then point out the novel features there-
10 of in claims.

In Fig. 1 of the accompanying drawings, I have shown several types of code suitable for use with apparatus embodying my invention. Figs. 2, 3 and 4 are diagrammatic views showing apparatus embodying my invention which is adapted for use with different pairs of the codes illustrated in Fig. 1.

In systems employing two-element track relays, broken-down rail joint protection is readily obtainable through the staggering of polarities of adjoining track circuits. This method is, however, of no avail in the case of circuits using the more simple and less expensive single element, two position track relay. The present invention
20 is directed to the provision of complete broken-down rail joint protection, irrespective of traffic conditions, in coded wayside and cab signaling systems, the track circuits of which employ the single-element code-following track relay.

Since staggered polarities cannot be used advantageously in track circuits of this type, I propose to stagger certain elements of the code supplied to adjoining track circuits and to provide apparatus distinctively responsive to the two types
30 of code, thereby preventing the display of false clear signals. With this arrangement, should the code of one track section pass over defective rail joints into the adjoining section, a restrictive signal will be displayed.

In carrying out the purpose of my invention, adjoining track circuits are supplied with currents of distinctive character. Obviously, the particular type of current which may be used as the carrier, and upon which may be impressed the characteristic which renders adjoining track circuits distinguishable from the standpoint of the code-following track relay is immaterial. For example, numerous codes met with in the signaling art, such as the frequency code, count code,
45 polarity code, time code, to name only a few, can be modulated in such a manner as to provide distinctive response in adjoining track circuits, for the purpose of broken-down rail joint detection.

In order not to complicate the disclosure unduly, I have chosen but two types of code, for

purposes of illustration, these being the frequency code, illustrated at A, B and C of Fig. 1, and the time code shown at D and E of the same figure.

Referring to Fig. 1, code C is the usual frequency code used in systems of wayside and cab 5 signaling and comprises, ordinarily, an alternating current carrier of any suitable frequency, upon which are impressed periodic variations occurring at the rate, for example, of 180, 120 or 80 per minute, as determined by traffic conditions. These variations can be impressed upon a direct current carrier with like effect.

Code A differs from code C only in that a relatively long "on" interval is interposed periodically in the code. This can be readily accomplished in a motor-driven cam type of code transmitter by mutilating that portion of the contact-operating cam which forms certain of the "off" code intervals, such as are shown dotted at a. Code A will be applied to a given track section, and it
10 will be understood that the codes of other periodic frequencies, which may be supplied to this track section under different traffic conditions, will be similarly modified by means of a long "on" interval.
15

Code B is similar to code A but instead of having a periodically recurrent long "on" interval, this code has a periodically recurrent long "off" interval. Code B is intended to be supplied to the track section adjoining the section supplied with code A. The long "off" interval of code B can likewise be readily obtained by mutilating the code transmitter cam to eliminate the "on" intervals shown dotted at b.
20

Codes D and E are time codes having long "on", short "off", and short "on", long "off" intervals, respectively. These codes may be used alternately in adjoining track sections in territory equipped for wayside signaling only, or for both wayside and cab signaling, provided that the locomotive equipment which is used is of such character as to be operative on impulses of the time code.
25

Referring now to Fig. 2, I have shown a stretch of railway track divided into sections 1—2 and 2—3, each of which is normally supplied with coded alternating current by means of a track transformer designated by the reference character T, with an exponent corresponding to the location. The normal traffic direction is from left to right, as indicated by the arrow. It will be noted that the codes of adjoining track sections are staggered, that is, the section immediately to the left of location 1 is supplied with code A, section 1—2 is supplied with code B, sec-

50
55

tion 2-3 with code A, and the section immediately to the right of location 3 is supplied with code B, these being the codes represented diagrammatically in Fig. 1.

- 5 The operation of the apparatus will first be explained with reference to section 2-3. With no train present, the rails of this section will normally be supplied with coded current from transformer T³, resulting in operation of the 10 code-following track relay TR², in step with the code. Relay TR² is of the direct current type, and is energized through the relay transformer RT² and rectifier R², the condenser C² and reactor X² being used to exclude propulsion current and foreign current of non-signaling frequencies. If relay TR² is of the alternating current type, it may be connected directly with the rails, eliminating the auxiliary apparatus.

It will be assumed that the periodic frequency 20 of code A is either 180, 120 or 80 per minute, according to the condition of traffic in advance sections. Relays F² and E² are frequency selective and are responsive, respectively, to the 180 and the 120 code. The energization of these relays 25 is obtained in the customary manner, by converting direct current from a source B-C applied over contacts 9-10 and 9-11 of relay TR², into alternating current in the secondary of decoding transformer DT². The output of transformer DT² is supplied to the usual decoding units DE² and DF² which comprise a condenser and a reactor tuned to the desired code frequency, as well as a rectifier if relays E² and F² are of the direct current type as is commonly the case. 30 The energizing circuits for relays E² and F² have not been shown in detail, since these circuits are the same as are commonly used in code systems of cab signaling, and are well-known.

Relays TRP², TP² and H² are controlled through 40 the operation of contacts 12-13 and 12-14 of relay TR², and in the present disclosure, these relays take the place of the usual 80 code relay. The release time interval of relay TRP² is so adjusted that this relay, having a pickup circuit 45 over back contact 12-14 of relay TR², will remain energized as long as relay TR² is following the ordinary impulses of the 180, 120 or 80 code frequencies, but will release during the periodically recurrent long on impulse which is 50 the distinguishing characteristic of the 180, 120 and 80 codes comprising code A. The release interval of relay TP² is such that the periodic opening of front contact 15-16 of relay TRP² will not deenergize this relay. Also, relay H² is 55 sufficiently slow acting to insure that the periodic closing of back contact 15-17 of relay TRP² will maintain relay H² in its energized position.

When the code supplied to transformer T³ is either 180 or 120, code transmitter CT² will supply 60 180 code to transformer T² for the rear track section 1-2, from a suitable alternating current source BX-CX, over a circuit which includes the front contacts 18-19 and 21-22 of relays TP² and H², as well as front contact 24-25 of 65 relay F², or alternatively, front contact 27-28 of relay E² and back contact 24-26 of relay F², according as relay TR² is following 180 or 120 code, respectively. If transformer T³ is supplied with 80 code, transformer T² will receive 120 code 70 over back contacts 27-29 and 24-26 of relays E² and F², and front contacts 21-22 and 18-19 of relays H² and TP². Consequently, as long as relay TR² is following any one of the code frequencies embraced within code A, the rear section 75 1-2 will receive either 120 or 180 code.

When a train enters section 2-3, relay TR², and therefore relays TP² and H², will become de-energized, and the 80 or restrictive code will be furnished to transformer T².

The indications of signal S² are controlled by 5 the relays TP², H², F² and F², in accordance with the code received by relay TR². The specific signal control circuits are not shown, as these are in accord with usual practice. Similarly, the indications of signal S¹ are controlled by the 10 decoding relay group for section 1-2.

Considering section 1-2 which is supplied with code B having a long off interval recurring periodically in the code, it will be noted that in this case, relay TRP¹ is controlled over a front 15 rather than a back contact of the code-following track relay in order that relay TRP¹ will have an opportunity to release during each long off interval, in the same manner that relay TRP² of section 2-3 was permitted to release during 20 each long on interval of code A. The control of relay H¹ is identical with the control of relay H², that is, relay H¹ remains energized provided that relay TR¹, and consequently relay TRP¹, follows the long off period in the code at intervals 25 which recur within the release period of this relay.

To explain the manner in which the circuit functions to provide broken-down rail joint protection, let it be assumed that section 2-3 is occupied, so that signal S² will display its most 30 restrictive indication, and that while section 2-3 is so occupied, the rail joints at location 2 are broken-down, permitting relay TR² to become energized and to follow code B which flows over the rail joints from section 1-2. The code frequency of code B, under this traffic condition will be 80. Were no protection provided, this 80 code might energize the 80 code relays of section 2-3, stepping up the code supplied to section 1-2 from 80 to 120. Thereupon, the 120 40 code relays of section 2-3 would respond to step up the code for section 1-2 to 180, which code when applied behind the train in section 2-3 might result in a false clear indication at signal S².

However, because of the absence of the long 45 on interval in code B, relay TRP² will not be de-energized periodically, thus providing no energizing impulses for relay H², as a result of which relay H² will remain deenergized. Therefore, the code frequency supplied to section 1-2 will remain at 80, and signal S² will continue to indicate the occupied condition of section 2-3.

If 80 or 120 code is being fed to section 2-3 at the same time that 120 or 180 code is being fed to the rear section 1-2, and the rail joints 55 break down, relay TR² will be following an irregular code, the resultant of codes A and B, which will ordinarily keep this relay energized almost continuously. If the code transmitters CT² and CT¹ are of the induction motor type and 60 are not synchronized, beat notes will usually occur, resulting from the two codes occasionally passing in and out of synchronism. Therefore, one or the other of relays TP² or H² will pick up or release occasionally, according as the two codes 65 A and B tend, at the moment, to annul or to aid each other, resulting in an occasional flashing indication being obtained at signal S², which aids detection of the faulty rail joint.

The manner in which relay TR¹ operates on 70 code B and provides protection against improper signal operation by code A from an adjoining section is as follows: It will be noted that relay TRP¹ is energized over a front contact of relay TR¹, and since code B has a long off interval, 75

relay TRP^1 will be deenergized at each long off interval, thereby maintaining the slow-releasing relay H^1 constantly picked up. The release time of relay TP^1 is sufficient to bridge the release period of relay TRP^1 , so that normally, relay TP^1 also remains picked up. If code A from an adjoining section either forward or in the rear of section 1-2 should flow in the rails of the section, the absence of the long off interval would prevent relay TRP^1 from releasing periodically, thus causing relay H^1 to release, and insuring the display of a restrictive indication at signals S^1 .

It will be apparent from the foregoing description that by staggering the codes which are applied to adjoining track circuits, complete broken-down rail joint protection can be obtained. The released condition of relay H^1 or relay H^2 may, of itself, be used to provide an indication that the rail joints at location 1 or 2 are broken-down.

In Fig. 3, I have shown how a standard code such as code C of Fig. 1, can be staggered with either of codes A or B, to provide the desired protection. Referring to Fig. 3, the decoding apparatus of this figure is similar to the standard decoding group used in frequency code systems of signaling with the exception that the usual 80 code relay is replaced by the two relays TP^4 and H^4 . When relay TR^4 is operating on code C, both relays TP^4 and H^4 remain constantly energized. Should code A from an adjoining section energize relay TR^4 , the long on interval of this code would cause relay TP^4 to release periodically, to cause flashing of the signal. If relay TR^4 is energized by code B, the long off interval of this code will similarly cause relay H^4 to release periodically, and to flash the signal.

Referring to Fig. 4, the circuits shown therein illustrate one way in which the principle of code staggering can be applied to a signaling system employing the time code, of which codes D and E of Fig. 1 are representative. To simplify the disclosure, direct current from a suitable battery source is used as the carrier for the code, instead of alternating current, and but one form of the characteristic code is supplied per track circuit by code transmitters CT , it being understood that for multiple aspect signaling each of codes D and E would in practice comprise modified forms based on different time ratios between the on and off intervals, for providing distinctive signal aspects in accordance with traffic conditions. Track sections 6-7 and 7-8 represent cut sections within a block, and the block signals and associated control circuits are omitted from the drawings as these are not essential for an understanding of the invention.

Considering section 1-8, the code supplied to track relay TR^7 by code transmitter CT^8 is code E of Fig. 1, and comprises relatively short periodic on intervals separated by relatively long off intervals. Relay TRP^7 is so designed that it will release during each long off interval of the code, and relay TP^7 is designed to bridge the release interval of relay TRP^7 . Therefore, each time that relay TRP^7 releases, relay TPP^7 will receive an impulse of energy, which will maintain relay TPP^7 constantly picked up, keeping the signal control circuit closed at front contact 30. Should relay TR^7 become accidentally energized by code D from the adjoining section, the short duration of the off interval of code D would prevent relay TRP^7 from releasing. Therefore, relay TPP^7 would become deenergized

and would open the signal circuit at contact 30, to provide the necessary protection.

In section 6-7, relay TRP^6 is designed to release during each long on interval of code D, and relay TP^6 is sufficiently slow-acting to bridge the release interval of relay TRP^6 . Therefore, relay TPP^6 will be maintained in its energized position by virtue of the periodic impulses of energy which it receives each time that the back contact of relay TRP^6 is closed. As a result, the signal control circuit will be maintained closed at front contact 31. The manner in which relay TPP^6 will release the open contact 31, should code E from an adjoining section falsely operate relay TR^6 , will be clear without added description.

It will be understood, of course, that the staggered codes of a given stretch of track need not belong to one group, such as the frequency code or the time code group, because one track circuit may be supplied with frequency code, such as code A, B, or C, and the adjoining track circuit with time code, such as code D or E, provided that decoding apparatus distinctively responsive to the particular code for the section be used.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. Apparatus for providing broken-down insulated rail joint protection comprising, in combination with two adjoining sections of railway track, means for supplying one of said sections with a plurality of different coded train governing rail currents upon at least one of which are impressed periodically recurrent variations according to a first pattern, means for supplying the other of said sections with a plurality of different coded train governing rail currents upon at least one of which are impressed periodically recurrent variations according to a second pattern, and decoding apparatus for each of said sections selectively responsive to said coded currents according as the variations thereof conform to said first or said second pattern. 50

2. In combination, two adjoining sections of railway track, means for supplying one of said sections with a plurality of different coded rail currents at least one of which is varied in a first periodically recurrent manner, means for supplying the other section with a plurality of different coded currents at least one of which is varied in a second periodically recurrent manner, a signal for each of said sections, a decoder for each of said sections for governing the signal associated therewith and selectively responsive to the codes supplied to its respective section, and means governed by each decoder for preventing a permissive indication of the associated signal in the event that the decoder becomes operated by coded rail current varied in the periodically recurrent manner from the adjoining section. 65

3. In a code system of railway signaling, the method of preventing the display of false signal indications resulting from feed-over around insulated rail joints, which comprises supplying to each of two adjoining track circuits a plurality of codes at least one of which is alternated with reference to a distinguishing time characteristic, and providing signal governing-decoding appa- 75

ratus selectively responsive to said codes for each track circuit, whereby a permissive signal indication will be given when said apparatus responds to codes supplied to the track circuit associated therewith, and a restrictive indication will be given when said apparatus responds to the alternated code from the adjoining track circuit.

5. In combination, a stretch of railway track divided into track circuit sections, means for supplying a plurality of codes of a given time pattern to alternate sections of said stretch, means for supplying a plurality of codes of a second time pattern to intervening sections of said stretch, decoding means for said alternate sections distinctly responsive to codes of said given time pattern, decoding means for said intervening sections distinctly responsive to codes of said second time pattern, and traffic governing apparatus controlled by the decoding means for said alternate and said intervening sections.

6. In combination, two adjoining sections of railway track one of which is supplied with coded rail current having a first characteristic code interval which recurs at given periodic times and the other of which is supplied with coded rail current having a second characteristic interval which recurs at said given periodic times, a code-following track relay for each of said sections, and a decoder for each of said sections controlled by the track relay associated therewith in such manner as to assume one or another condition according as the track relay is following coded rail current having said first or said second characteristic interval, respectively, whereby the condition of said decoder indicates whether the track relay is following rail current supplied to the section associated therewith or rail current supplied to the adjoining section.

7. In combination, a first section of railway track, a second section of railway track adjoining therewith, means for supplying said first section with a code having a periodically recurrent "on" interval of relatively long duration, means for supplying said second section with a code having a periodically recurrent "off" interval of relatively long duration, and a signal governing decoder for each of said sections responsive to said codes in such manner as to assume a signal governing condition in response to the code supplied to its respective section but to assume an inoperative condition in response to the code supplied to the adjoining section.

8. In combination, a section of railway track supplied with a code upon which is impressed a periodically recurrent characteristic interval of relatively long duration, a code-following track relay for said section, a first relay controlled by said track relay in such manner as to remain energized at all times except when the track relay is following said characteristic interval of the code, a second relay controlled over a front contact of said first relay and capable of bridging the deenergized interval of said first relay, a third relay controlled over a back contact of said first relay and capable of bridging the energized interval of said first relay, and traffic governing apparatus controlled by said second and third relays.

9. In combination, a first section of railway track, a second section of railway track adjoining therewith, means for supplying said first section with a code having a periodically recurrent "on" interval of relatively long duration, means for supplying said second section with a code having a periodically recurrent "off" interval of

5. relatively long duration, a code-following track relay for each of said sections, a control relay for said first section governed by the associated track relay in such manner as to maintain its energized condition provided the code supplied to said first section contains said periodically recurrent "on" interval, a control relay for said second section governed by the track relay associated therewith in such manner as to maintain its energized condition provided the code supplied to said second section contains said periodically recurrent "off" interval, and traffic governing apparatus controlled by each of said control relays.

10. In combination, a first section of railway track, a second section of railway track adjoining therewith, means for supplying said first section with one of a first group of codes selected in accordance with traffic conditions in advance of said first section, each code of said first group being characterized by a periodically recurrent "on" interval of relatively long duration, means for supplying said second section with one of a second group of codes selected in accordance with traffic conditions in advance of said second section, each code of said second group being characterized by a periodically recurrent "off" interval of relatively long duration, decoding apparatus for said first section selectively responsive to codes of said first group as well as to the presence of said periodically recurrent "on" interval in said codes, decoding apparatus for said second section selectively responsive to codes of said second group as well as to the presence of said periodically recurrent "off" interval in said codes, and traffic governing apparatus controlled by the decoding apparatus for said first and said second sections.

11. In combination, a first section of railway track, a second section of railway track adjoining therewith, means for supplying said first section with a plurality of coded rail currents, means for supplying said second section with a similar plurality of coded rail currents upon at least one of said currents is impressed a periodically recurrent characteristic variation, a signal for said first section, a decoder for said first section selectively responsive to said coded rail currents, and means governed by said decoder for preventing the display of a permissive indication by said signal in the event that said decoder becomes operated by the coded rail current supplied to said second section, and having said periodically recurrent characteristic variation impressed thereon.

12. In combination, a stretch of railway track divided into track circuit sections alternate ones of which are supplied with rail current of a given code and intervening sections of which are supplied with rail current of said given code modified by a periodically recurrent characteristic variation, and decoding apparatus for each of said alternate and said intervening sections capable of assuming one condition when energized by said given code and another condition when energized by said given code as modified by said characteristic variation, whereby the condition of said apparatus provides an indication of the integrity of the insulated rail joints between said alternate and said intervening sections.

13. In combination, a first section of railway track, a second section of railway track adjoining therewith, means for supplying said first section with rail current of a given code, means for supplying said second section with rail cur-

rent of said given code upon which is impressed a periodically recurrent characteristic variation, a code-following track relay for said first section, a control relay governed by said track relay 5 in such manner that said control relay will assume one condition when said track relay is following said given code and another condition when said track relay is following the code supplied to said second section, and traffic governing apparatus controlled by said control relay.

10 13. In combination, a first section of railway track, a second section of railway track adjoining therewith, means for supplying said first section with a plurality of coded rail currents comprising substantially uniform periodic "on" intervals separated by substantially uniform "off" intervals of relatively shorter duration, means for supplying said second section with a plurality of coded rail currents comprising substantially uniform periodic "off" intervals separated by substantially uniform "on" intervals of relatively shorter duration, a decoder for each of said sections selectively responsive to the coded currents supplied to the section associated therewith, and traffic governing means controlled by said decoders.

15 14. In combination, a first section of railway track, a second section of railway track adjoining therewith, means for supplying said first section with coded rail current of a first code comprising substantially uniform periodic "on" intervals separated by substantially uniform "off" intervals of relatively shorter duration, means for supplying said second section with coded rail current comprising substantially uniform periodic "off" intervals separated by substantially uniform "on" intervals of relatively shorter duration, a code-following track relay for said first section, a first relay controlled by said track relay in such manner as to remain energized during the "off" periods of said first code and to become deenergized during each "on" period of said first code, a second relay controlled over a front contact of said first relay and capable of bridging the deenergized interval of said first relay, a third relay controlled over a back contact of said first relay and a front contact of said second relay and capable of bridging the energized interval of said first relay, and a traffic governing apparatus controlled by said third relay.

20 15. In combination, a first section of railway track, a second section of railway track adjoining therewith, means for supplying rail current of a first and of a second code to said first and said second section respectively, a code-following track relay for said first section, and means controlled by said track relay effective for preventing the supply of rail current of said second code to said second section if said track relay is following said second code.

25 16. In combination, a first section of railway track, a second section of railway track adjoining therewith, means for supplying rail current of a first and of a second code to said first and said second section respectively, a code-following track relay for said first section, and a protection relay controlled by said track relay and effective for preventing the supply of rail current of said second code to said second section

if said track relay is following said second code.

30 17. In combination, a first section of railway track, a second section of railway track adjoining therewith, means for supplying said first section with rail current varied according to a first code, a code-following track relay for said first section, a decoding relay controlled by said track relay, a source of current varied according to a second code, a protection relay controlled by said track relay and said decoding relay in such manner as to assume one condition when the track relay is following current varied according to said first code and another condition when the track relay is following current varied according to said second code, and means controlled in accordance with the condition of said protection relay for supplying current from said source to the rails of said second section.

35 18. In combination, a first section of railway track, a second section of railway track adjoining therewith, means for supplying said first section with a first code having a periodically recurrent "on" interval of relatively long duration, means for supplying said second section with a second code having a periodically recurrent "off" interval of relatively long duration, a code-following track relay for said first section, a decoding relay controlled by said track relay, a protection relay controlled by said track relay and said decoding relay in such manner as to assume a first or a second condition according as said track relay is following said first or said second code respectively, and means effective when the protection relay occupies said second condition for preventing the supply of said second code to said second section.

40 19. In combination, a first section of railway track, a second section of railway track adjoining therewith, means for supplying said first section with a first code having a periodically recurrent "on" interval of relatively long duration, means for supplying said second section with a second code having a periodically recurrent "off" interval of relatively long duration, a code-following track relay for said first section, a decoding relay controlled by said track relay, a protection relay energized over a front contact of said decoding relay and having a release time insufficient to bridge the long "off" interval of said second code, and means effective when the protection relay is deenergized for preventing the supply of said second code to said second section.

45 20. In combination, a first section of railway track, a second section of railway track adjoining therewith, means for supplying rail current of a first and of a second code to said first and said second section respectively, a code-following track relay for said first section, a protection relay, a decoding relay controlled over a front contact of said protection relay, means for controlling said protection relay by said track relay, said protection relay being designed to remain energized if the track relay is following said first code but to release if said track relay is following said second code, and means controlled by said protection relay for governing the supply of said second code to said second section.
